UNITED STATES PATENT OFFICE

ARTHUR R. LEUKHARDT, OF DETROIT, MICHIGAN, ASSIGNOR TO THE WESTINGHOUSE AIR BRAKE COMPANY, OF WILMERDING, PENNSYLVANIA, A CORPORATION OF PENNSYLVANIA

VACUUM OPERATED HORN

Application filed October 10, 1930. Serial No. 487,744.

This invention relates to signal horns, and more particularly to a vacuum operated horn for motor vehicles, adapted to be operated by the suction derived from the intake manifold 5 of an internal combustion engine.

One object of my invention is to provide an improved vacuum operated horn, which is simple in construction and positive in action.

10 Another object of my invention is to provide a vacuum operated horn in which the operation is facilitated by augmenting the fluid pressure opposing the vacuum or sub-atmospheric pressure.

15 In the accompanying drawing, the single figure is a diagrammatic view, showing my improved signal horn in section and associated with the engine cooling system of a motor vehicle.

20 The improved signal horn may comprise a casing 1, a cover plate 2 secured to the casing 1 by screws 3, and a flexible diaphragm 4, which is clamped between flanges of the casing and cover plate. The casing 1 carries a central annular sleeve section 5, the outer edge of which is in close proximity to the diaphragm 4. Secured in the casing 1 in axial alignment with the sleeve 5 is a sound 70

25 projecting or amplifying horn 6. Secured centrally of the diaphragm 4 by means of a nut 8 and said member has a valve chamber 9 in which is mounted a poppet valve 10, having a fluted stem 11 which extends through an opening in a screw 75

30 plug 12, and a fluted stem 13 at the opposite side, which extends through a bore in the member 7.

The cover plate 2 has a central hub 14, in 40 which an adjustable screw 15 has screw-threaded engagement, said screw being in axial alignment with the stem 13. A coil spring 16 is mounted in chamber 17 of the hub 14 and acts on the diaphragm 4. A coil spring 17 acts on the valve 10 and urges same 45 to its seat.

For creating a partial vacuum in the chamber 18 at one side of the diaphragm 4, a valve device is provided comprising a casing 19 having a valve chamber 20 connected to a pipe 21 leading to a source of vacuum, such

as the suction intake manifold (not shown) of an internal combustion engine. In said chamber is mounted a valve 22, subject to the pressure of a spring 23 tending to seat the valve, and carrying an operating stem 24, 55 which extends out through an opening in the casing 19 and is provided at its outer end with a push button 25. The valve 22 controls communication from chamber 20 to chamber 26, which is connected to diaphragm chamber 18, 60 through pipe 27 and a restricted port 28.

According to one feature of my invention, the chamber 29 at the opposite side of the diaphragm 4 is supplied with fluid under pressure when the vehicle engine is running, and for this purpose, a tube 30 is connected to the chamber 29 and said tube is provided at its outer end with a conical inlet 31. Said inlet is disposed adjacent to the usual blower fan 32, which is mounted as usual, between the radiator 33 and the engine 34, the fan being driven from the engine shaft through a belt 35.

When the engine of the vehicle is running, the fan 32 operates to force an under pressure through the tube 30 into the diaphragm chamber 29.

In operation, when it is desired to sound the horn, the valve 22 is unseated by depressing the button 25, so that a partial vacuum is created in the diaphragm chamber 18, which normally is at atmospheric pressure. The diaphragm 4 is then flexed to the right by the fluid pressure in chamber 29. This movement causes the stem 13 to engage 80 the end of the screw 15, so that the valve 10 is unseated. Fluid at atmospheric pressure within the horn 6 is then vented to diaphragm chamber 18, and the port 28 being somewhat restricted, the pressure builds up 85 in diaphragm chamber 18, so that the diaphragm 4 assisted by spring 16 is flexed to the left, permitting the valve 10 to again seat. With valve 10 seated, a partial vacuum is again created in diaphragm chamber 18, and the movement of the diaphragm is repeated. The diaphragm 4 is thus caused to vibrate, so as to create sound by vibrating the column 90 of air in the horn 6.

With the vehicle engine running, the fluid 100

pressure in diaphragm chamber 29 is raised above atmospheric pressure, so that the action of the diaphragm 4 is intensified. When the diaphragm 4 is flexed to the right, the outlet area from chamber 29 to the horn 6 is increased, which tends to reduce the pressure in the chamber 29 to atmospheric pressure and thus facilitate the return movement of the diaphragm 4 toward the left when the 10 return movement is started by the building up of pressure in the chamber 18, due to the opening of the valve 10.

While one illustrative embodiment of the invention has been described in detail, it is 15 not my intention to limit its scope to that embodiment or otherwise than by the terms of the appended claims.

Having now described my invention, what I claim as new and desire to secure by Letters 20 Patent, is:

1. A sounding device comprising a flexible diaphragm having a chamber at one side, means for creating a partial vacuum in said chamber, a member mounted centrally of said 25 diaphragm, a valve carried and supported by said member for controlling communication from said chamber to the atmosphere, and means operated upon flexing the diaphragm for opening said valve.

2. A sounding device comprising a flexible diaphragm having a chamber at one side, means for creating a partial vacuum in said chamber, a member mounted centrally of said 30 diaphragm, a valve mounted in and supported by said member for controlling communication from said chamber to the atmosphere, and means operated upon flexing said diaphragm in one direction for opening said valve.

3. A sounding device comprising a flexible diaphragm having a chamber at one side, means for creating a partial vacuum in said chamber, a member mounted centrally of said 35 diaphragm, a valve mounted in said member and having oppositely extending guide stems, and means for engaging one of said stems to open said valve and connect said chamber to the atmosphere upon flexing said diaphragm in one direction.

4. A sounding device comprising a flexible diaphragm having a chamber at one side, means for causing said diaphragm to vibrate upon the creation of a partial vacuum in the chamber at one side of the diaphragm, and 45 means for amplifying the fluid pressure in the chamber at the opposite side of the diaphragm.

5. The combination with a sounding device comprising a flexible diaphragm having a 50 chamber at one side and means for causing said diaphragm to vibrate upon the creation of a partial vacuum in the chamber at one side of the diaphragm, of a blower fan for increasing the fluid pressure in the chamber 55 at the opposite side of the diaphragm.

6. The combination with a sounding device comprising a flexible diaphragm having a chamber at one side and means for causing said diaphragm to vibrate upon the creation of a partial vacuum in the chamber at one side of the diaphragm, of a blower fan for effecting the cooling of a vehicle internal combustion engine, and means for conveying fluid compressed by said fan to the chamber at the opposite side of said diaphragm. 70

7. The combination with a sounding device comprising a flexible diaphragm having a chamber at one side and means for causing said diaphragm to vibrate upon the creation of a partial vacuum in the chamber at one side of the diaphragm, of an internal combustion engine, a blower fan for effecting the cooling of said engine, and a tube connected to the chamber at the opposite side of said diaphragm and having a nozzle in proximity to said fan, through which air compressed by said fan is conveyed to said chamber. 75

In testimony whereof I have hereunto set my hand, this 4th day of October, 1930.
